UNITED STATES PATENT OFFICE.

HARRY FOX, OF CINCINNATI, OHIO.

WINDOW-SASH FASTENER.

1,407,022.

Specification of Letters Patent. Patented Feb. 21, 1922.

Application filed May 1, 1920. Serial No. 378,105.

To all whom it may concern:

Be it known that I, HARRY FOX, a citizen of the United States, residing at Cincinnati, in the county of Hamilton and State of Ohio, have invented certain new and useful Improvements in Window-Sash Fasteners, of which the following is a specification.

My invention relates to improvements in window sash adjusting and locking mechanism. One of its objects is to provide for adjusting the lower or upper or both sashes to relatively different positions in the window frame. Another object is to provide for securely locking either of the sashes in closed or partly open position, so as not to be liable to be opened from the exterior. Another object is to provide for temporarily throwing the sash locking means out of operation until again required for use. My invention also comprises certain details of form, combination, and arrangement, all of which will be fully set forth in the description of the accompanying drawings in which:

Fig. 1 is a plan of a window frame and sashes with my improved locking and adjusting means applied thereto.

Fig. 2 is an enlarged plan of one of the locking members.

Fig. 3 is a view similar to Fig. 2 showing a different position of the operative parts.

Fig. 4 is a section taken on line 4—4 of Fig. 2.

Fig. 5 is a section taken on line 5—5 of Fig. 3.

Fig. 6 is a plan view of one of the window frame engaging members detached.

Fig. 7 is a view similar to Fig. 6 illustrating a modification.

Fig. 8 is a perspective view of a rack to be employed with the locking member of Fig. 7.

The accompanying drawings illustrate the preferred embodiments of my invention, in which 14 represents the window frame, 15 the lower sash and 16 the upper sash. The sashes may be counterbalanced by means of weights and cords, or not, since my locking means may be employed to advantage in either event.

My improved adjusting and locking means is adapted to be applied to the upright stile of the sash at either the right hand side or the left hand side, as may be preferred, by inverting the locking member.

The locking and adjusting apparatus comprises a frame 17 having screw eyes 18 to

enable it to be firmly attached to the upright stile 19 of the sash, preferably near the center of said stile, so that a person from the exterior of the window would find it difficult to reach in and release the sash lock, in the event that the window was partly open. The frame 17 has a recess 20 in which are located engaging or locking members 21 and 22, said locking members being pivotally supported upon the journal rods 24 and 25, preferably rigidly connected at opposite ends to the frame 17 and serving to strengthen the frame and to firmly lock the members 21 and 22 in position relative to the frame.

The members 21 and 22 are preferably of stamped sheet metal in order to avoid liability of breakage, and also to insure sufficient accuracy to render said members practically interchangeable. The main portion of the members 21 and 22, which are counterparts one of the other, are of irregular curved or cam shaped outline, journaled eccentrically, and having recesses therein to serve as housing spaces for their respective actuating springs. The outer engaging faces of said members 21 and 22 are preferably for ordinary purposes plain curved faces presenting sufficient surface in engagement with the window frame so as to firmly hold the sash in position against displacement without liability of injuring or marring the window frame. Recesses 26 are cut out to enable one end of the actuating springs to project out beyond the members 21 and 22 into engagement with the frame 17, or a stationary part carried thereby. The members 21 and 22 are also provided with actuating handles, 27 and 28, preferably formed integral by stamping. The actuating springs 29 are coiled about the journal rods 24 and 25 with one end seated in a perforation 30 in the member 21 or 22, while the opposite end of the spring passes through the recess 26 to engage a rod or stud 31 carried by the frame 17, thereby throwing the tension of the springs 29 upon the locking members 21 and 22 to cause the cam or eccentric faces of the members 21 and 22 to move toward each other as indicated by the arrows in Figs. 1 and 2, and to thereby engage the face of the facing strip 32 of the window frame opposite the lower sash, or a separating strip 33 interposed between the two sashes and in position to be engaged by the locking members 21 and 22 of the upper

sash. With the cam faces of the locking members 21 and 22 in engagement with the window frame, any pressure exerted to force one of the sashes upwardly will tend to the locking of a member 21 more firmly with the window frame, while any pressure downwardly on either sash will tend to cause a locking member 22 to engage more firmly with the window frame, and thus effectively 10 lock the sashes against movement in either direction. Said locking members also provide for adjusting the sashes, or either of them to partly open positions for the purpose of ventilation without liability of their 15 being forced further open by pressure from the exterior. The locking members are also in such position as to prevent their being operated or released by a person from the exterior.

20 It is sometimes desirable to lock the members 21 and 22 out of engagement with the window frame on one or both sashes temporarily, and in order to do so I provide a leaf spring member 34 having latch members 35 25 to respectively engage the handles 27 and 28 of the members 21 and 22 and to lock them in substantially the position shown in Fig. 3 out of operative relation to the window frame, until it is desired to release them, 30 when pressure is applied to the head or push-button 37 to depress the latch members 35 and release them from the handles 27 and 28.

For use on car windows, and for similar 35 purposes where the windows are subjected to considerable vibration, I preferably mill

or rib the engaging faces of the members 21 and 22 as illustrated at 21' in Fig. 7, and provide in connection therewith rack members 36 of metal to be applied to and attached to the window frame in position to be engaged by the ribbed faces of the locking members. 40

The apparatus herein illustrated and described is capable of considerable modification without departing from the principle of 45 my invention.

What I claim is:

1. A sash fastener comprising a frame, a pair of spring actuated fastening members 50 eccentrically pivoted on said frame, each member having a handle extension, and a spring latch mounted on the frame between said handles and having a pair of projections each of which is engageable with one of the 55 handles to hold the fastening members in released position.

2. A sash fastener comprising a frame, a pair of fastening members mounted in said frame, each member comprising a cupped 60 sheet metal head having a handle extension, an eccentric pivot pin extending from the frame through said head, and a spring coiled around said pin and housed in said head and connected thereto at one end, the 65 flange of the cupped head having a recess through which the other end of the spring projects to contact with the frame.

In testimony whereof I have affixed my signature.

HARRY FOX.
